UNITED STATES PATENT OFFICE,

VICTOR FINSTEN, OF TORONTO, ONTARIO, CANADA.

GARMENT-POCKET.

1,013,757.

Specification of Letters Patent.

Patented Jan. 2, 1912.

Application filed July 3, 1911. Serial No. 636,683.

To all whom it may concern:

Be it known that I, VICTOR FINSTEN, a subject of the King of Great Britain, and resident of the city of Toronto, county of

5 York, Province of Ontario, in the Dominion of Canada, have invented certain new and useful Improvements in Garment-Pockets; and I do hereby declare that the following is a full, clear, and exact description 10 of the same.

The invention relates to improvements in garment pockets, as described in the following specification and illustrated in the accompanying drawings that form part of the 15 same.

The invention consists essentially in the novel construction and arrangement of the webs of the fabric forming the pocket and the material of the garment and pocket flap.

20 The objects of the invention are, to devise a form of double pocket in which either section may be closed the one independent of the other, thus providing a secret pocket, and further to enable the wearer of the garment to change the appearance of the pocket flaps at will.

In the drawings, Figure 1 is a perspective view of a portion of a garment showing the pocket with the double flap exposed. Fig. 2 30 is a perspective view showing the lower flap hidden. Fig. 3 is a perspective view showing both upper and lower flaps hidden. Fig. 4 is a perspective view showing both of the pocket flaps in their outer position with the 35 upper one turned downwardly and the lower one partially broken away disclosing the arrangement of the locking tongue. Fig. 5 is a sectional view through the pocket as shown in Fig. 1. Fig. 6 is a sectional view 40 through the pocket as shown in Fig. 2. Fig. 7 is a sectional view through the pocket as shown in Fig. 3. Fig. 8 is a sectional view through the pocket as shown in Fig. 4. Fig. 9 is a sectional view showing the upper flap 45 hidden and the lower one exposed.

Like numerals of reference indicate corresponding parts in each figure.

Referring to the drawings, 1 is the fabric of the garment having a pocket slot 2 cut 50 therein.

3 is a web of lining secured to the inner side of the fabric 1 below the slot 2 and extending downwardly and forming one side of the pocket.

55 4 is a web of lining secured at its upper edge to the inner side of the upturned por-

tion 5 of the garment fabric above the pocket slot and extending downwardly and secured at its bottom and side edges of the bottom and side edges of the front lining 3. 60

6 is a web of lining secured at the bottom and side edges between the front and back linings 3 and 4 and dividing the pocket into front and back sections. The upper edge of the center web 6 terminates directly opposite the pocket slot 2 and is securely fastened at the sides. 65

7 is the pocket flap secured intermediate of its depth to the upper edge of the center web 6 firmly sewn thereto at the ends and inwardly toward the center but the center portion is left unsewn, thereby providing a passage or opening 8 between the said flap and center web. 70

9 is a tab preferably formed of cloth the 75 same as the garment fabric and secured between the back lining 4 and the upturned portion 5 of the garment fabric, said tab being arranged central of the width of the pocket and extending downwardly and 80 formed with a button hole at its bottom end.

10 is a button secured to the outer face of the garment fabric below the pocket slot 2 and covered by the bottom portion of the pocket flap when the same is in its outer 85 position.

A pocket constructed as described may be changed in various ways so as to have a different appearance and so as to close or lock either the inner pocket alone or both 90 pockets together. The flap 7 being secured centrally is divided into upper and lower flaps 11 and 12 and both the upper and lower flaps may be arranged to the outside as shown in Figs. 1, 5 and 8. 95

In Fig. 5 the tab 9 is lying loosely within the rear pocket section but in Figs. 4 and 8 the tab is shown inserted through the passage 8 and pocket slot and is secured at the lower end to the button 10. As the tab 100 is secured at its upper end to the upturned portion 5 it will be seen on reference to Fig. 8 that both the inner and outer pockets will be securely closed so that the hand cannot be placed in the pocket without the tab being released and withdrawn. 105

If it is desired to have the pocket appear as a vest pocket with access to both pockets the tab 9 is left free and the lower flap 12 is pushed into the front pocket section as 110 shown in Figs. 2 and 6. Either of said pocket sections may then be used as desired

without interference. If it is desired to close the inner pocket and leave the outer pocket free the upper flap 11 may be turned in as shown in Figs. 7 and 9 or if it is desired 5 to lock the inner pocket and retain both flaps to the outside the tab 9 may be inserted through the opening 8 and the lower end left free within the outer pocket section.

In Fig. 7 the flaps are entirely hidden so 10 that the pocket appears as shown in Fig. 3.

From this description it will be seen that many combinations of flaps may be had and however the flaps are arranged either one or the other or both of the pocket sections 15 may be locked as described.

What I claim as my invention is:—

1. The combination with a garment pocket of the kind described having a partition extending up to the pocket slot, of a flap 20 joined to the upper edge of said partition and having a slot adjacent to said joining, a tab secured within the pocket and adapted to extend through said flap and pocket slots to close the pockets.

25 2. In a garment pocket, the combination with a garment having a pocket slot therein, of a pocket member formed of three plies of material having the front and back ply secured to the inner side of the garment 30 above and below the pocket slot and the center web terminating opposite the pocket

slot, a pocket flap secured to the upper edge of said center web and from the sides inwardly leaving a central opening between said flap and said web, and a tab secured 35 within the pocket above the pocket slot adapted to extend through the opening between said center web and flap.

3. In a garment pocket, the combination with a garment having a pocket slot therein, of a pocket member formed of three plies of material having the front and back ply secured to the inner side of the garment above and below the pocket slot and the center web terminating opposite the pocket 40 slot, a pocket flap secured to the upper edge of said center web and from the sides inwardly leaving a central opening between said flap and said web, a tab secured within the pocket above the pocket slot adapted to 45 extend through the opening between said center web and flap, said tab having a button hole therein, and a button secured to the outer face of the garment below the pocket slot.

Signed at the city of Toronto, Ontario, Canada, this 15th day of June, 1911.

VICTOR FINSTEN.
